UNITED STATES PATENT OFFICE.

EUGENE G. LUENING, OF CHICAGO, ILLINOIS, ASSIGNOR TO DAVIS-BOURNONVILLE COMPANY, OF NEW YORK, N. Y., AND CHICAGO, ILLINOIS, A CORPORATION OF NEW YORK.

METAL-CUTTING TIP.

1,106,724.

Specification of Letters Patent. Patented Aug. 11, 1914.

Application filed April 4, 1913. Serial No. 758,772.

To all whom it may concern:

Be it known that I, EUGENE G. LUENING, a citizen of the United States, residing at Chicago, county of Cook, State of Illinois, have made a certain new and useful Invention in Metal-Cutting Tips, of which the following is a specification.

This invention relates to metal cutting tips and particularly to tips employed in the oxygen-acetylene or similar gas mixture cutting processes.

The object of the invention is to provide a construction of cutting tips which is simple, efficient, and economical to make.

A further object is to provide a tip of the nature referred to wherein provision is made for entraining a low pressure gas by the use of a high pressure gas for the preheating and reheating flames either or both, in the same tip with the jet of gas or gas mixture which effects the cutting.

Other objects of the invention will appear more fully hereinafter.

The invention consists substantially in the construction, combination, location and relative arrangement of parts, all as will be more fully hereinafter set forth, as shown in the accompanying drawing, and finally pointed out in the appended claims.

In the drawing Figure 1 is a view in the central longitudinal section on the line 1, 1, Fig. 2, of a cutting tip embodying the principles of my invention. Fig. 2 is a transverse section of the same on the line 2, 2 Fig. 1. Fig. 3 is an inside face view of the removable head end portion of the tip.

In the use of cutting tips of the nature and class employed for cutting metals with gas mixture flames, it is customary to provide means for supplying a preheating flame as well as what may be termed a reheating flame, one or both, to the metal to be cut in addition to the cutting jet itself, the preheating flame being applied to the metal, in advance of the cutting flame, with reference to the direction of the cut, while the reheating flame follows the cutting jet, and serves to clear out the kerf made by the cutting jet. The cutting jet consists of pure oxygen alone, while the preheating and reheating flames are required to develop intense heat. Consequently the preheating and reheating flames are ordinarily sustained by a gas in conjunction with oxygen, or a mixture of suitable gases in the required proportion to

produce the necessary heat. The preheating and reheating flames, being required to develop a high degree of heat, may be sustained by either high or low pressure gases, or mixture of gases, such for instance as acetylene gas, coal gas, Blau gas, illuminating gas, or the like, used in conjunction or mixed with oxygen, or other combustion supporting gas under high pressure. It has been found in practice that when high pressure is used in conjunction with low pressure gas, or is to be mixed therewith, the flow of the high pressure gas may be utilized to entrain or cause a corresponding correct flow of the low pressure gas in the required proportion to form a proper mixture to meet the requirements. It is among the special purposes of my present invention to provide a single tip structure wherein this result is accomplished in a simple and efficient manner with respect to the oxygen or other gas mixture of high pressure, with acetylene gas, coal gas, Blau gas, illuminating gas, or the like of low pressure, for the preheating and reheating flames, one or both, and without regard to the supply of gas for the cutting flame or jet.

In the drawing I have shown a simple structure as an illustrative embodiment of my invention, wherein 5 is the body of the tip longitudinally through which are drilled the ducts or passages 6, 7, and 8, the duct 6 constituting the channel through which the cutting flame or jet supply gas is conducted, while 7 and 8, are, respectively, the channels or ducts through which the preheating and reheating flame gases are conducted. It will be observed that these ducts are parallel to each other and they lie in the same plane centrally and longitudinally through the tip, thus in use bringing the several flames at the delivery end of the tip in line with each other in the direction in which the cut is to be made, the preheating flame in advance and the reheating flame in the rear of the cutting flame. In practice, and in order to bring the maximum heat of the preheating flame to bear on the surface of the metal to be cut, the metal of the tip body is cut away or jogged off at the delivery end of the duct, as indicated at 9. Since ordinarily the preheating flame is required to develop a more intense heat than the reheating flame the duct 7, is made of larger transverse sectional area than that of the duct 8, as shown. The

- receiving end of the tip body is counter-bored centrally thereof, and the counterbore is interiorly threaded to receive the exteriorly threaded portion 10, of a removable end portion or plug 11. This end portion or plug is provided with a longitudinal central bore 12, which is thus brought into line and registered with the bore 6 of the tip body, for the passage of the cutting flame gas.
- 10 This plug is also provided with a circumferential channel 13, to which, when the tip is inserted in the usual head, is supplied the oxygen or other gas under high pressure which is to be mixed with low pressure gas to supply the preheating and reheating flames. The plug or portion 11, is suitably off-set from the end surface of the tip body to form or there is otherwise formed a peripheral channel 14, to which, when the tip is inserted into its head, the low pressure gas is supplied. The ducts 7, 8, terminate in this peripheral channel and preferably in cone shaped depressions 15. Carried by the plug or portion 11, are nipples 16, 17 having central longitudinal bores 18, 19 arranged in central relation and alignment with the ducts, 7, 8, respectively, the said bores 18, 19, both opening into the peripheral channel 14, while the ends of the nipples are presented 30 toward and directed into the conical depressions 15. The nipples are suitably secured in seats formed in the plug 11 to receive them. By making the plugs 11, removable the seats for the nipples may be readily and 35 easily formed therein and the nipples inserted and secured in place in said seats, and the tip assembly completed by simply screwing the threaded part 10 of the plug into the threaded counterbore of the tip body.
- 40 It will be observed that with the construction shown, and as above described, the nipples operate as injectors to cause the flow of high pressure gas as it flows from the channel 13, through the bores of the nipples and on 45 into the ducts 7, 8, to entrain and carry along into said ducts with it the low pressure gas, thus securing an injector action in the feed and supply of the low pressure gases.
- 50 Having now set forth the object and nature of my invention, and a construction embodying the principles thereof, what I claim as new and useful and desire to secure by Letters Patent is,—
- 55 1. In a metal cutting flame tip, a tip body
- having a cutting flame gas supply duct, and an auxiliary flame gas supply duct, an end portion removably connected to said tip body, and a nipple carried by said end portion and arranged in line with said auxiliary 60 flame gas duct, said nipple and duct respectively receiving a high pressure and a low pressure gas supply source.
2. In a metal cutting flame tip, a tip body having a cutting flame gas supply duct and 65 an auxiliary flame gas supply duct arranged in parallel relation to each other, a removable end portion for said tip body, said end portion having peripheral channels to receive, respectively, high and low pressure 70 gas supplies, and a nipple carried by said end portion and arranged in line with said auxiliary flame gas duct, said nipple and duct respectively communicating with said peripheral channels.
3. In a metal cutting flame tip, a tip body having a central duct and an auxiliary duct parallel thereto, said auxiliary duct having a conically shaped mouth, an end portion for the tip body having peripheral channels 80 respectively to receive high and low pressure gas supplies, and a nipple presented into said mouth, said nipple and mouth respectively communicating with said channels.
4. In a metal cutting flame tip, a tip body having a central duct and an auxiliary duct parallel to each other, and a removable end portion for the tip body, said end portion having a nipple with its delivery end presented toward the mouth of the auxiliary duct, said nipple and mouth respectively receiving a high and low pressure gas supply.
5. In a metal cutting flame tip, a tip body having a central duct and auxiliary ducts arranged on opposite sides thereof and in parallel relation to each other, said body having an end portion, said end portion having nipples respectively presenting toward and into proximity to the mouths of said auxiliary ducts, said nipples and mouths respectively receiving high and low pressure gas supply.
- In witness whereof I have hereunto set my hand this 25th day of March, 1913, in the 105 presence of the subscribing witnesses.
